MILL SCREEN

Farrell G. Lively, Cherokee, Okla., assignor to
Earnest M. Wetmore, Tonkawa, Okla.

Application June 30, 1947, Serial No. 758,018

4 Claims. (Cl. 241—88)

1

This invention relates to feed grinders or ensilage cutters, and more particularly to the screens therefor which cooperate with the rotor in reducing materials to comminuted form. Screens of this type usually include a transverse bar or bar segments, and considerable difficulty is experienced with the binder twine and tough hay when hay and bundled feed stuff are being reduced. The tough hay and binder twine, particularly when wet, pile up on the bars and choke the passages through the screens. Also, such bars have little cutting effect and cause the feed to be discharged in aropy condition. The bars when worn or dulled require replacement of the entire screen with a new one, involving needless expense.

Therefore, the principal objects of the present invention are to provide a screen having staggered blades with cutting edges which more effectively cut wet twine and tough hay and to provide an arrangement of blades which allows the cut material to pass freely through the screen without clogging.

Further objects of the invention are to provide a screen with cutting blades sharpened on both sides so that when one side becomes worn, the screen may be reversed in the grinder to present the other edges; to provide blades which may be removed from the screen and replaced when both cutting edges become worn; to provide a hammer mill screen with bars having sharpened forward and rear edges for cutting material; to provide a hammer mill screen with staggered blades arranged transversely of the direction of travel of material past the blades; and to provide improved elements and arrangements thereof in a screen of this character which is simple, economical to manufacture and efficient in operation.

In accomplishing these and other objects of the present invention, I have provided improved details of structure, the preferred form of which is illustrated in the accompanying drawings, wherein:

Fig. 1 is a vertical longitudinal section through a hammer mill provided with a screen embodying the features of the present invention.

Fig. 2 is a perspective view of a screen embodying the features of the present invention.

Fig. 3 is a partial plan view of the screen particularly illustrating the staggered arrangement of the blades.

Fig. 4 is an enlarged sectional view through the screen taken on the line 4—4, Fig. 3.

Referring more in detail to the drawings:

1 designates a hammer mill or cutter for reducing hay ensilage and similar crops and which includes a base 2 carrying spaced side walls, one of which is shown at 3, and end walls 5 and 6 to form a casing 7. The upper ends of the side walls taper upwardly and inwardly as at 8 and

2

9, and the upper portion 10 of the end wall 5 follows the shape of the side walls. The upper portion 11 of the end wall 6 curves toward the portion 10 but terminates short thereof to provide a discharge opening or outlet 12. Connected to the outlet 12 is a discharge duct 13 through which material is discharged from the casing 7.

Carried between the side walls and extending from the end wall 5 to the end wall 6 is a plate 15 which cooperates with the curved portion 11 and a screen member 16 to complete a substantially cylindrical rotor chamber 17.

Journalled in the sides of the casing coaxially of the rotor chamber is a drive shaft 18 carrying a rotor 19 having a plurality of radially extending hammers 20 that pivot freely in one direction on the rotor for cooperating with the screen in reducing material that is fed into the rotor chamber through an inlet 21 indicated by the dotted lines (Fig. 1).

The above described structure, with the exception of the screen, is that of a conventional type grinder which specifically forms no part of the present invention.

The screen 16 includes a frame 22 having arcuate side rails 23 and 24 connected by end rails 25 and 26. Extending laterally into the space between the arcuate side rails 23 and 24 to a point slightly beyond midway of the median arc of the screen are blades 27. The blades 27 are in the form of triangular shape and may comprise ordinary sickle blades having apertures aligning with apertures in the side rails 23 and 24 for attachment by rivets or similar fastening devices which permit ready removal of the blades when worn or dulled.

The triangular shape of the blades provides diverging edges 28 and 29 which are sharpened to form bevelled cutting edges 30 and 31. The cutting edges 30 and 31 of the blades are adapted to lie in alignment with the outer surface 36 of the side rails 23 and 24 of the frame 22 which provide clearance between the cutting blades and the hammers of the rotor. The blades on the respective side rails are also preferably staggered as shown in Figs. 2 and 3, which arrangement assures proper cutting of the material and leaves ample space for discharge of material into the discharge duct. The triangular shape of the blades and their cutting edges facilitates shredding of the material and prevents balling up of the material and adherence thereof to the blades of the screen. It will be noted on inspection of the drawing that the triangular blades provide a tortuous passageway from one end of the screen to the other which is of substantially uniform width with cutting edges on both sides thereof. This is important because materials that are deflected laterally by the cutting edges of the blades 55 on one side contact the facing cutting edges of

the blades on the opposite side. Thus, both side edges of the blades are effective while the material is being pushed through the passageway by the hammers. The angular position of the cutting edges also cooperates with the hammers in producing a shearing action on the material which assures cutting up of the wet binding twine and tough materials.

The concave screen is supported in the upper portion of the housing by spaced guide members 33 on each of the side walls to provide slots which receive the edges of the side rails 23 and 24, the screen being inserted through a slot 34 formed by the spacing of the end 11 of the end wall 6 from the discharge duct. The screen is moved through the guides until the end rail 25 engages the end 35 of the curved plate 15. The screen is held in place by a stop member 36 enclosing the slots through which the screen is inserted.

Operation of an ensilage cutter or hammer mill equipped with a screen constructed and assembled as described is as follows:

Material or other ensilage, such as feed, cut corn-stalks and/or grasses in either wet or dry state, is supplied to the rotor chamber of the mill through the conventional feed opening 21. Upon operation of the drive shaft 18, the rotor is turned in a clockwise direction (Fig. 1) at sufficient speed to circumvolve the material about the rotor chamber and across the screen, whereby centrifugal force acts on the material to hold it while it is acted upon by the hammers and pushed thereby through the tortuous passageway of the screen to be acted upon by the blades. The twine and stringy material are directed against the sharpened edges of the triangular-shaped blades 27 to assure comminution thereof so that it does not hang up on the blades of the screen.

Since the cutting edges 30 of the blades in the direction of rotation are apt to become dull before the cutting edges on the retractive sides, the screen 16 may be removed and placed in reverse position so that the cutting edges 31 will be in position to cut and chop the material going through the mill, thus providing a longer lasting screen and obviating numerous replacements of the blades. However, when the blades are worn on both edges, they are readily removable and replaced, thereby obviating the necessity of replacing the entire screen.

It will be apparent from the foregoing that I have provided an improved screen for ensilage cutters or hammer mills which will be of longer life and obviate replacement at frequent intervals, and one which will operate without clogging by stringy material as it passes through the mill.

What I claim and desire to secure by Letters Patent is:

1. A screen for hammer and like mills including laterally spaced arcuate rails having a curvature adapted to substantially correspond with curvature of the rotor chamber in which the screen is to be used, bars connecting ends of the rails to provide a frame adapted for insertion over the discharge opening of the mill, and substantially flat blades projecting from the rails inwardly of the frame with the blades on one rail staggered with respect to the blades on the other rail to provide a tortuous passageway, each of said blades having oppositely disposed cutting edges converging toward the opposite rail with the cutting edges of the blades on one rail facing the cutting edges of the blades on the opposite rail to provide cutting edges at both sides of the portions of said passageway therebetween.

2. A screen for hammer and like mills including laterally spaced arcuate rails having a curvature adapted to substantially correspond with curvature of the rotor chamber in which the screen is to be used, bars connecting ends of the rails to provide a frame adapted for insertion over the discharge opening of the mill, and substantially flat blades projecting from the rails inwardly of the frame with the blades on one rail staggered with respect to the blades on the other rail to provide a tortuous passageway, each of said blades having oppositely disposed cutting edges converging toward the opposite rail with the cutting edges of the blades on one rail facing

the cutting edges of the blades on the opposite rail to provide cutting edges at both sides of the portions of said passageway therebetween, said cutting edges being of a length to extend beyond the median point between the rails of said frame.

3. A screen for hammer mills including laterally spaced arcuate rails having a curvature adapted to substantially correspond with the curvature of the rotor chamber in which the screen is to be used, substantially flat triangular

blades arranged in staggered relation on the respective rails to provide a tortuous passageway therebetween and having apertured base portions registering with apertured portions of the rails, fastening devices extending through said apertures to secure the blades, said blades having oppositely disposed cutting edges converging toward the opposite rail with the cutting edges of the blades on one rail facing the cutting edges of the blades on the opposite rail to provide cutting edges at both sides of the portions of the passageway therebetween.

4. A screen for hammer mills including laterally spaced arcuate rails having a curvature adapted to substantially correspond with the curvature of the rotor chamber in which the screen is to be used, substantially flat triangular

blades arranged in staggered relation on the respective rails to provide a tortuous passageway therebetween and having apertured base portions

registering with apertured portions of the rails, fastening devices extending through said apertures to secure the blades, said blades having oppositely disposed cutting edges converging toward the opposite rail with the cutting edges of the blades on one rail facing the cutting edges of the

blades on the opposite rail to provide cutting edges at both sides of the portions of the passageway therebetween, said blades being of a size relatively to the spacing of the rails whereby the apex formed by the oppositely disposed cutting edge of one blade extends beyond the median point between said rails.

5. A screen for hammer mills including laterally spaced arcuate rails having a curvature adapted to substantially correspond with the curvature of the rotor chamber in which the screen is to be used, substantially flat triangular

blades arranged in staggered relation on the respective rails to provide a tortuous passageway therebetween and having apertured base portions

registering with apertured portions of the rails, fastening devices extending through said apertures to secure the blades, said blades having oppositely disposed cutting edges converging toward the opposite rail with the cutting edges of the blades on one rail facing the cutting edges of the

blades on the opposite rail to provide cutting edges at both sides of the portions of the passageway therebetween, said blades being of a size relatively to the spacing of the rails whereby the apex formed by the oppositely disposed cutting edge of one blade extends beyond the median point between said rails.
